UNITED STATES PATENT OFFICE.

ARTHUR B. BELLOWES, OF PITTSBURG, PENNSYLVANIA.

STEEL GONDOLA CAR.

SPECIFICATION forming part of Letters Patent No. 729,257, dated May 26, 1903.

Application filed August 21, 1902. Serial No. 120,556. (No model.)

To all whom it may concern:

Be it known that I, ARTHUR B. BELLOWES, of Pittsburg, in the county of Allegheny and State of Pennsylvania, have invented a new and useful Steel Gondola Car, of which the following is a full, clear, and exact description, reference being had to the accompanying drawings, forming part of this specification, in which—

10 Figure 1 is side elevation of my gondola car in which the side sill 2 is a flanged pressed metal shape. Fig. 2 is a similar view showing the side sill a rolled shape. Fig. 3 is a vertical cross-section on the line III III of Fig. 1. Fig. 4 is a sectional detail view showing the attachment of the floor-beam to the side sill of the car shown in Fig. 2. Figs. 5, 6, and 7 are similar sectional views showing modified constructions.

15 20 In the drawings, 2 represents the side sill of a car, which in Fig. 1 is a flanged beam, pressed with its ends tapering or of less depth than the middle, and in Fig. 2 is a rolled shape of uniform cross-section from end to end.

25 3 is the center sill, and 4 represents the side plates, which are formed, as shown in Fig. 3, with top and bottom flanges 5 5'. These flanges, as shown at 5', need not be integral with the plates, but may be constituted by separate angle-pieces riveted to the margins of the plates. The side plates are riveted at the flanges to the side sills and the floor-plates 6 are riveted to the side plates and preferably, also, to the side sills.

30 35 In Figs. 3 and 4 I show the floor-plates inserted between the flanges of the side sill and side plates and held thereto by rivets which pass through these members.

40 45 In Fig. 5 the floor-plate 6 is flanged downwardly at 7, and this flange is riveted to the side plate 4 above the connection of the side plate to the side sill. This flange is preferably an integral part of the floor-plate, but is not necessarily so.

In Fig. 6 the construction is similar to that of Fig. 5, except that the flange of the floor-plate is directed upwardly, the meeting flanges of the side plate and side sill are directed outwardly, the side sill is a rolled shape,

while in Fig. 5 it is a pressed shape, and the floor-beams 8 are cut away to accommodate the inturned flanges.

In Fig. 7 the construction is like that of Fig. 5, except that the meeting flanges of the side sill and side plate are directed outwardly and the floor-beam 8 is not cut away.

In Figs. 6 and 7 I show short angles 9 applied to the side sills as a support for the floor-beams.

In each of the figures I show side stakes 10 secured to the side plates and side sills for stiffening the structure.

My invention affords great strength with economy and simplicity of construction. 65

Those skilled in the art will be able from the foregoing description to modify the construction without departing from my invention as herein claimed, since

What I claim is—

1. A metal gondola car having flanged side sills, side plates extending above said sills, said side plates having horizontally-extending flanges at their lower margins and being secured to the side sills, horizontally-extending floor-plates, all of which are secured to the same one of said parts, and vertically-extending side stakes secured to the sides and side sills; substantially as described. 75

2. A metal gondola car having flanged side sills, and side plates extending above them, said side plates having flanges at their margins and secured to the side sill, horizontal floor-plates all of which are secured to the side plates, and side stakes secured to the side plates and side sills; substantially as described. 80

3. A metal gondola car having flanged side sills, and side plates, said side plates having flanges at their margins and secured to the side sills, horizontal floor-plates all of which are secured to both the side plates and the side sill, and side stakes secured to the side plates and side sills; substantially as described. 90

4. A metal gondola car having flanged side sills, and side plates, said side plates having flanges at their margins and secured to the side sill, horizontal floor-plates, all of which are secured to one of said parts, a center sill, 100

and side stakes also secured to said parts; substantially as described.

5. A metal gondola car having flanged side sills, and side plates, said side plates having flanges at their margins and secured to the side sills, horizontal floor-plates, all of which are secured to both the side plates and the side sill, side stakes secured to the side plates

and side sills, and a center sill; substantially as described. 10

In testimony whereof I have hereunto set my hand.

ARTHUR B. BELLOWS.
